UNITED STATES PATENT OFFICE.

THOMAS SINGLETON, JR., OF NEW BEDFORD, MASSACHUSETTS.

DESIGN FOR A GLASS DISH.

SPECIFICATION forming part of Design No. 22,203, dated February 7, 1893.

Application filed September 22, 1892. Serial No. 446,627. Term of patent 7 years.

To all whom it may concern:

Be it known that I, THOMAS SINGLETON, Jr., of New Bedford, in the county of Bristol and State of Massachusetts, have invented and produced a new and original Design for Glass-ware, of which the following is a specification, reference being had to the accompanying drawings, illustrating the same, and showing it embodied in a glass dish or shallow bowl. Figure 1 is a plan view and Fig. 2 a central vertical section of a dish or bowl containing my design.

My design consists in a series of indentations extending in curved lines at a tangent from a circular space and constituting a star or "daisy" shaped figure, the points of which extend nearly to the rim of the dish.

2c *a* are the indentations extending tangentially in curved lines from the circular space *b* and meeting at the points *c*. From the ver-

tices of the spaces between the points *c* extend a number of indentations *d*. The circular space *b* is ornamented by a number of intersecting lines and an inner circular figure from the center of which radiate other indentations. A number of other indentations *e* extend tangentially from the space *b* crossing each other and forming fields ornamented in various ways. But the distinguishing characteristic of my design is the star or 30 "daisy" shaped figure formed by indentations extending tangentially from a central figure in curved lines to the edge of the dish.

What I claim is:

The design for an ornamented glass dish as 35 herein described and shown.

THOMAS SINGLETON, JR.
